ASH TRAY OR SIMILAR ARTICLE

Herman E. Menold, 11347 Davenrich St.,
Santa Fe Springs, Calif.

Filed Mar. 13, 1964, Ser. No. 78,996

Term of patent 14 years

(Cl. D85—2)

FIGURE 5 is a view similar to FIGURE 1 showing another embodiment of my design wherein the ash tray is provided with four cigarette snuffer elements and four cigarette rest grooves as shown.

I claim:

The ornamental design for an ash tray or similar article, as shown and described.
